BRASSIERE DISPLAY PACKAGE

Carl Braun, Riverside, Conn., assignor to Maiden Form Brassiere Co., Inc., New York, N. Y., a corporation of New York

Application October 30, 1953, Serial No. 27,393

Term of patent 7 years

(Cl. D80—5)

FIG. 1.

FIG. 2.

FIG. 3.

Fig. 1 is a front view of a brassiere display package showing my new design;

Fig. 2 is a side view; and

Fig. 3 is a top plan view thereof.

The design is characterized by the particular configuration of the cut-out in the front of the package through which is exposed a brassiere cup portion, extending from the apex of the cup to the lower edge thereof.

I claim:

The ornamental design for a brassiere display package, as shown and described.
